Atty,

UNITED STATES PATENT OFFICE.

FRANK E. PETERSON, OF CHICAGO, ILLINOIS, ASSIGNOR TO F. A. HARDY & COMPANY, OF CHICAGO, ILLINOIS, A CORPORATION OF ILLINOIS.

READING-GLASS.

1,044,814.

Specification of Letters Patent.

Patented Nov. 19, 1912.

Application filed October 2, 1911. Serial No. 652,471.

To all whom it may concern:

Be it known that I, FRANK E. PETERSON, a citizen of the United States, residing at Chicago, in the county of Cook and State of Illinois, have invented a new and useful Reading-Glass, of which the following is a specification.

My invention relates to improvements in reading glasses which are designed to be held in the hand of the user; and the objects of my improvement are the provision of adjustable facilities for steadyng the glass while in use, and which will also maintain the glass in usable position with relation to the article under inspection when the hand has been withdrawn from it.

I attain these objects by the mechanism illustrated in the accompanying drawing, in which—

20 Figure 1 is a perspective of my improved reading glass with the legs unfolded or in open position; Fig. 2 is an end view of my improved reading glass, with the legs folded up or in closed position; Fig. 3 is a fragmentary detail rear view, partially in section, of the connection between the leg and the frame, showing the lock for holding the leg in open position; and Fig. 4 is a section on line 1—1 of Fig. 3.

30 Similar reference numerals refer to similar parts, throughout the several views.

The reference numeral 1 designates a suitable reading lens, which is conveniently made of rectangular outline, although the principle of my invention is applicable to other forms of lens. The lens, 1, is held in a frame comprising the side bars, 2, which are provided with the longitudinal channels, 3, into which extend the sides of the lens, 1, 40 and the end plates, 4 and 5. The end plates are secured to the side bars by screws, 6, or any other suitable means.

To the central portion of the end plate, 5, is secured a suitable handle, 7. Extending 45 substantially at right angles from either end of the end plate, 4, are short projections or arms, 8, in the outer ends of which are provided the indentations or cut out places, 9. Pivotally secured to the frame 50 above the short arms, 8, by means of the screws, 6, are the legs, 10, which are slotted at a point, 11, which comes opposite to the indentations, 9, upon the short arms, 8. A small plate, 12, is provided, which has a 55 projecting portion or pawl, 13, thereon,

which extends into the slot, 11, upon the legs, 10, and which will extend into the indentation, 9, upon the short arms, 8, when it is brought opposite thereto by the swinging of the legs, 10. In order to secure the 60 plate, 12, and pawl, 13, in position, a plate, 14, which is larger than the slots at 11, is secured in front of the legs, 10, to the plate, 12, through the said slots by means of the screw, 15, and a spring, 16, is provided for 65 pressing the projection or pawl, 13, into engagement with the indentation, 9. The sides of the plate, 12, extend slightly beyond the edges of the legs, 10, and are milled so as to facilitate the disengagement of the 70 projection, 13, from the indentation, 9, manually, when it is desired to fold the legs into closed position. The inner corner of the arms, 8, at 17 are rounded so as to permit the pawl, 13, to clear said corner when 75 the legs, 10, are being opened.

The legs, 10, are made of such length that when they are open and in contact with the book or paper under inspection it will be in good focus.

It will now be perceived, and especially by reference to Fig. 1, that the user of the glass may move it over the book or paper while the legs, 10, are contacting therewith. This will contribute largely to the steadiness 85 of the glass and the efficiency of the service that may be had from it. It is also possible to withdraw the hand entirely from the glass, when it will be supported by the handle, 7, and legs, 10, in an inclined position, 90 such as is most advantageous for the inspection of the article under it. When the glass is not in use, or it is desired to use it without the supporting legs, the legs may be folded, as shown in Fig. 2, in which position they 95 will be entirely out of the way, and the glass may be put into a case, or in the pocket, or used in any manner in which it could be, if it were not provided with the legs.

I do not wish to be held to the specific embodiment of my invention disclosed in the drawings, as it is obvious that many variations therefrom may be made without departing from its spirit or scope.

Having described my invention, what I claim as new and desire to secure by Letters Patent, is:—

1. A reading glass, comprising a lens, a handle therefor, and legs extending at sub- 110

stantially right angles to the plane of said lens and handle and forming, with said handle, an inclined support for said lens.

2. A reading glass, comprising a lens, a handle, legs pivoted to swing into and out of the plane of said lens, and means for securing said legs in said last-mentioned position.

3. A reading glass, comprising a lens, a handle therefor, and means for steadyng the glass in use comprising two legs of suitable

length, pivotal mountings for said legs, and means for securing said legs in proper position.

In testimony whereof, I have hereunto 15 set my hand in the presence of two witnesses.

FRANK E. PETERSON.
